David Stow, of Logansport,

Letters Patent.

The schedule referred to in these Letters Patent and making part of the same, containing a description in the words of the said David Stow, himself of his improvement in the art of sawing timber.

To all to whom these presents shall come. Be it known that I, David Stow of the County of Vanderburgh, and State of Indiana, have invented a new and useful improvement in the art of sawing timber, and that the following is a full and exact description of the construction and operation of the said improvement (or machine) as invented or improved by me. There are two large beams placed permanent on an inclined position of seven feet two twenty four in length, on which the carriage runs. There are small wheels in the carriage, which wheels run on those permanent beams. There is a rag or straight line with cog on each side of the carriage, which are placed under the beams so as to lap on each side of those timbers to guide her up and down straight. The rag or cog'd part of the carriage, as she moves, runs over the shaft of the wheel called the stop wheel, which shaft has two wallowers, one, and extends across under those permanent timbers so that the wallowers meet the cog or cog of the carriage on both sides, inclining to bear on the stop wheel, but from those wallowers, so that the cog of one, ranges with the space of the other. If this shaft be casting the rings are cast on, if wood, they are cut out & should be iron rings, bound to the shaft; those wallowers have clearance in each one, and the stop wheel has 176 bags; this wheel runs into a hollow of twenty two rings, which is on the shaft of the

16287

of the wheel, called the swift wheel, which has 106 spgs, which runs into a wallow or clevisings on a shaft, that has a crank to move the law, there is also a small fly wheel on this shaft to cause the crank to stop in center, and on the end of the shaft opposite to the crank, there is a post, on a horizontal timber, that has a joint in a post above one and will raise and fall at the other end, to the shoulder of stones in a post to keep it out of gearing; and in gearing which is done by a lever drawn between the fore and aft posts when dopped out of gearing, the carriage is trud back by the slip wheel; the lever when raised is locked fast to the permanent timbers, and there is a catch on the carriage to unhook it just at the time the law has run his cut out. There is a post set in the permanent beams, with a spring on it for the carriage to stop against. The movable beam blocks be at the back of the car, that her stopping place will suit all lengths of timber; all the cogs of wheels and wings of wallows must be two inches cog and space which regulates her feed to one fourth of an inch, to give her lefft feed the wallow on the shaft of the swift wheel must be lessened, which is necessary to suit all timbers; at short cuts, with quick motion and lefft feed is preferred in the above plan. The place of applying the power to run her, is to the swift wheel; when horse power is used is the principal intention of her construction, is applied, the gearing must be attached by a wallow to her cog, if by water, by putting a water wheel on her shaft.
